UNITED STATES PATENT OFFICE.

JULIUS LAMBERT, OF HOBOKEN, NEW JERSEY.

DESIGN FOR A PURSE AND BELT THEREFOR.

40,341.

Specification for Design.

Patented Nov. 9, 1909.

Application filed May 22, 1909. Serial No. 497,813. Term of patent 7 years.

To all whom it may concern:

Be it known that I, JULIUS LAMBERT, a citizen of the United States, residing at Hoboken, in the county of Hudson, State of New Jersey, have invented a new, original, and ornamental Design for Purses and Belts Therefor, of which the following is a specification, reference being had to the accompanying drawing, forming a part thereof.

The figure is a perspective view of a purse and a belt therefor.

I claim:

The ornamental design for a purse and a belt therefor, as shown.

In testimony whereof, I affix my signature, in the presence of two witnesses.

JULIUS LAMBERT.
